UNITED STATES PATENT OFFICE

AAGE JENSEN, OF LOS ANGELES, CALIFORNIA

PORTABLE LIQUID-TREATING APPARATUS

Original application filed June 6, 1927, Serial No. 196,775. Divided and this application filed October 10, 1928. Serial No. 311,555.

This invention relates to portable liquid treating apparatus, and is in part a division of my application Serial Number 196,775, filed June 6, 1927.

5 The object of this invention is to provide apparatus for treating various liquids, such as milk, cream, etc., by means of a rotating coil or stirrer, which coil or stirring element is supplied with a temperature-changing medium such as hot or cold liquid or gas. A further object is to construct a device in a portable and self-contained form, which will permit of its being readily and easily moved about from one container to another.

15 The present invention contemplates the use of an immersion heating or cooling element which may be submerged in a body of liquid to be treated and which is thereafter agitated to cause its radiation surface to come into contact with a maximum amount of the fluid recurrently within a minimum period of time, whereby greater heat transfer will take place than is accomplished when the liquid is substantially motionless with relation to the 20 heating or cooling medium, making the device particularly applicable for use in emulsifying, pasteurizing, cooling, and otherwise treating liquids to change their temperature.

One form which my invention may assume 30 is exemplified in the following description and illustrated in the accompanying drawings, in which

Fig. 1 shows an elevation, partly in section, of a form of the device, in which power 35 is employed for rotating the coil;

Fig. 2 shows a side elevation of the upper portion of the device illustrated in Fig. 1;

Fig. 3 shows a sectional view, taken on the line V—V of Fig. 1.

40 In the drawings, I show a portable apparatus embodying suitable power means for rotating a coil. This form of device includes a helical coil 120 carried at the lower end of a hollow shaft 121, which shaft at its upper 45 end is connected to a suitable motor 122 and driven thereby. Said shaft and motor are supported by a thrust-bearing 123 which is provided with lugs 124 to rest upon the top of a container 125.

50 The hollow shaft contains within it a tu-

bular member 126 which forms the inlet for steam or liquid passing to the coil. This tubular member 126 is spaced from the walls of the hollow shaft 121 and the annular space between constitutes the outlet for the steam 55 or liquid from the coil. Communicating with the inlet is a flexible pipe 127 having a control valve 128 through which steam or other liquid may be admitted to the coil from a distant source. Communicating with the outlet from the coil is a flexible pipe 129, also provided with valve means, and through which the steam or liquid which has circulated through the coil is discharged to any 60 suitable point.

The motor as here shown is an electric motor, the power for operating which is supplied through conduits 130, although obviously a steam or water motor may be employed and flexible connections provided for supplying it with the necessary liquid or gas. Suitable handles 131 are provided for transporting and positioning the device.

The operation of this form of apparatus is the same as those described in the above-mentioned application, except that no external supporting means are required, such as overhead tracks and the like, the entire device being adapted to be supported on the top of the container. As shown in Figs. 1 75 and 3, it is preferred to have the supporting legs 124 so arranged that the rotating coil will occupy an eccentric position within the container, as a result of which a better agitation of the liquid within the container may 80 be had.

Having thus described my invention, what I claim and desire to secure by Letters Patent is:

1. An apparatus for treating liquids, comprising a coil through which a temperature-changing medium may be circulated, a shaft on which the coil is mounted, said shaft being provided with inlet and outlet conduits 90 for the treating medium, a motor carried by the shaft for rotating the same, flexible connections leading to the shaft for supplying the treating medium thereto, and means on the shaft, engageable with a container, for 95 100

supporting the entire device during its operation.

2. An apparatus for treating liquids, comprising a coil through which a temperature-changing medium may be circulated, a shaft on which the coil is mounted, said shaft being provided with inlet and outlet connections for the treating medium, a motor carried by the shaft for rotating the latter, flexible connections leading to the shaft, for supplying the treating medium thereto, flexible connections leading to the motor for supplying a driving medium thereto, a bearing on the shaft, and means on the bearing, engageable with a container, for supporting the entire device during its operation.
